Patented May 14, 1912.

UNITED STATES PATENT OFFICE.

RUBBIN J. WOODARD, OF DANVILLE, ILLINOIS.

DINNER-PAIL.

1,026,543.

Specification of Letters Patent.

Patented May 14, 1912.

Application filed April 11, 1911. Serial No. 620,372.

To all whom it may concern:

Be it known that I, RUBBIN J. WOODARD, a citizen of the United States, residing at Danville, in the county of Vermilion and 5 State of Illinois, have invented new and useful Improvements in Dinner-Pails, of which the following is a specification.

This invention relates to dinner pails, the object of the invention being to provide an 10 improved attachment therefor whereby the drinking water can be readily drawn from the water compartment of the pail without necessitating the removal of the cover of the pail.

15 In the drawing, forming a portion of this specification and in which like numerals of reference indicate similar parts in the several views:—Fig. 1 is a side view of the pail. Fig. 2 is a section therethrough on line 2—2 of Fig. 1. Fig. 3 is a section on line 3—3 of Fig. 1. Fig. 4 is a perspective view of the draw-off tube. Fig. 5 is a perspective view of the vent tube.

The pail 1 includes a lower section 1 and 25 an upper section 2, the latter being designed so as to be partly fitted into the former as shown in Fig. 2 of the drawing. The section 2 is provided with a continuous stop bead 3 which is adapted to rest upon the 30 reinforcing bead 4 at the upper end of the bottom section 1 so as to limit the adjustment of the section 2 in the section 1 as will be understood. This construction is also such that the bottom of the upper section 35 can be spaced from the bottom of the lower section to form an intervening chamber A for water.

The draw-off tube 6 is preferably formed 40 from a single piece of sheet material stamped to provide a vertical substantially semi-cylindrical portion 7 whose walls are arranged in opposing relation to the walls of the lower section of the pail, being arranged exteriorly of the pail and provided with an 45 attaching flange 8 which may be soldered or otherwise suitably secured to the walls of the section 1 of the pail. The flange or member 8 is of a length slightly greater than the semi-cylindrical portion 7 and of 50 a length equal to the distance between the reinforcing bead 4 and the upper edge of the bottom of the lower receptacle respectively. From this construction it will be 55 readily understood that the portion of the member 8 which extends beyond the upper and lower ends of the semi-cylindrical por-

tion 7 is adapted to be snugly fitted between the bead 4 and the upper edge of the bottom of the lower receptacle, whereby the tube 6 is securely retained in position upon 60 the said section, and the member 8 protected from accidental displacement from the receptacle. Adjacent to the bottom, the section 1 is provided with an opening 9 which 65 opens directly into the lower end of the portion 7 of the draw-off member, the opposite end of the member being arranged in open communication with a tube or mouth piece 10.

A vent tube 11 is secured to the lower section 1 of the pail, and as shown, this tube is constructed with a vertical leg 12 and an outwardly and downwardly curved branch portion 13, the latter being arranged in open communication with the outside air. 75 The lower end of the vertical leg 12 of the tube carries a tongue 14 which extends through the opening 15 in the lower section 1 and secured to such section by solder or other suitable fastening means, the said 80 tongue being adapted to lessen the strain on the section at the side thereof. The top section of the pail is provided with a removable cover 16.

From the construction described it will 85 be seen that water may be placed in the chamber A and when the same is desired for use the mouth piece 10 is placed in the mouth of the user and through suction the water may be drawn from the chamber as 90 is obvious, it being understood that the vent tube hereinbefore described allows the air to enter the chamber to replace the liquid as it is drawn off.

I claim:—

A pail comprising a member including upper and lower sections, said lower section being formed to provide a reinforcing bead, a cover fitting the upper section, the bottoms of the sections being spaced from each 95 other to form an intervening liquid chamber, the bottom of the lower section being formed with an angular flange surrounding the said section, a draw-off tube embodying a member stamped from a single piece of 100 material and formed to provide a vertical substantially semi-cylindrical portion arranged in opposing relation to the wall of the lower section, and a substantially rectangular attaching flange secured to the said 105 section, the said tube having one of its ends opening directly into the chamber and hav-

ing its opposite end provided with a mouth piece, the said flange having a portion thereof extending beyond the upper and lower ends of the semi-cylindrical portion adapted to be snugly fitted between the said bead and annular flange of the bottom of the lower receptacle, whereby the tube is securely retained in position upon the section

and the said flange protected from accidental displacement therefrom.

In testimony whereof I affix my signature in presence of two witnesses.

RUBBIN J. WOODARD.
